(57) **CLAIM**

The ornamental design for a extruded rail for linear motor, as shown and described.

DESCRIPTION

FIG. 1 is a perspective view of the ornamental design for the extruded rail for linear motor;

FIG. 2 is a right side view of the extruded rail for linear motor of FIG. 1, the left side view being a mirror image of the right side view shown;

FIG. 3 is a top view of the extruded rail for linear motor of FIG. 1;

FIG. 4 is a bottom view of the extruded rail for linear motor of FIG. 1;

FIG. 5 is a front view of the extruded rail for linear motor of FIG. 1; and,

FIG. 6 is a rear view of the extruded rail for linear motor of FIG. 1.

In these drawings, the solid lines illustrate the claimed ornamental design, whereas the broken lines illustrate environmental features that form no part of the claimed ornamental design.
